UNITED STATES PATENT OFFICE.

ANDREW PATERSON, OF MCKEESPORT, PENNSYLVANIA, ASSIGNOR TO THE NATIONAL TUBE WORKS COMPANY, OF SAME PLACE.

MACHINE FOR FORMING WAGON-AXLES.

SPECIFICATION forming part of Letters Patent No. 374,694, dated December 13, 1887.

Application filed February 28, 1887. Serial No. 229,129. (No model.)

To all whom it may concern:

Be it known that I, ANDREW PATERSON, of McKeesport, Allegheny county, Pennsylvania, have invented certain new and useful Improvements in Forming Machines, of which the following is a specification.

This invention pertains to machinery for giving special forms to metal tubes. As an illustration of the line of operations of my improved machine, I refer to a hollow wagon-axle formed from parallel tubing, having at each end tapering reductions to receive the wagon-wheels, and also end nipples to receive the axle-nuts, the axle being formed by properly operating upon metal tubing. I refer to the wagon-axle as a mere example of the work of my machine.

My improvements will be readily understood from the following description, taken in connection with the accompanying drawings, in which—

Figure 1 is a side elevation of a machine serving to illustrate my improvements; Fig. 2, a plan of the same; Fig. 3, a front elevation of the rear housing with attached parts, some being shown in vertical section; Fig. 4, a rear elevation of a portion of the rear housing with various parts in place; Fig. 5, an end view of one of the nipple-roll carriers which is supported by the rear housing; Fig. 6, a diagram illustrating the relation of rolls to each other and to the tube being formed; Fig. 7, a side elevation of a portion of a tubular wagon-axle, shown in connection with an elementary forming-roll, such forming-roll being designed to serve in illustrating a peculiar principle of operation which I prefer to involve in my machine; Fig. 8, a side elevation of a fluted forming-roll; and Fig. 9, an end elevation of a portion of a forming-roll, showing one of the flutes.

In the drawings, A indicates the rear housing of the machine, the same consisting of a vertically-disposed plate provided with a vertical slot to receive sliding roll-boxes and with a horizontal slot crossing the same and arranged to receive sliding nipple-roll carriers; B, the front housing, similar to the rear housing, but not necessarily provided with slots for nipple-roll carriers, the two housings being set in parallel planes; C, roll-boxes fitted to slide in the vertical slots of the housing; D, a pair of rolls journaled in the roll-boxes and hav-

ing a length and diameter suited for the range of work desired of the machine; E, a front bearing supported by the front housing, the axis of this bearing passing between the axes 55 of the main rolls D; F, a chuck fitted to revolve freely in the front bearing; G, a driving-shaft journaled in the housings above the main rolls and intended to receive rotary motion and serve in imparting the proper motions to 60 the various parts of the machine; H, a pair of vertical shafts to the rear of the rear housing and disposed one on each side of the plane of the driving shaft and main rolls.

J is a worm-gearing serving to transmit motion from the driving-shaft to the vertical shafts, one worm upon the driving-shaft engaging a worm-wheel upon each of the vertical shafts, one of the vertical shafts being set farther to the front than the other; K, worm- 70 gearing serving to transmit motion from the vertical shafts to the shafts of the main rolls, the main-roll shafts projecting rearwardly beyond the rear housing, each a sufficient distance to permit its worm-wheel to engage the 75 worm of its appropriate vertical shaft; L, a top shaft supported in the housings above and parallel to the driving-shaft; M, vertical screws disposed alongside the housings and engaging each an appropriate roll-box in such manner 80 that when all of the screws are simultaneously revolved the main rolls will be brought together or moved apart; N, worm-gearing serving to transmit motion from the top shaft to the vertical screws, the arrangement of this worm- 85 gearing being similar to that of the gearing J; O, gearing serving to transmit motion from the driving-shaft to the top shaft, the same consisting of a pair of spur-gears, the one on the top shaft being loose on the shaft and provided with a clutch-hub; P, gearing similar to the gearing O, but involving an intermediate gear, so as to cause a reversal of direction of motion, the wheels of this gearing being proportioned to give to the top shaft a velocity of 90 motion different from that given by the gearing O; Q, a clutch upon the top shaft fitted to be thrown into engagement with either of the spur-gears upon the top shaft, so as to serve in locking either gear to the top shaft; R, nipple-roll carriers, the same consisting of blocks 95 fitted to slide in the horizontal slot of the rear

housing; S, nipping-rolls supported by the nipple-roll carriers, such rolls being of a length and size and contour suited to the form of nipple desired upon the tube being operated upon; T, a rack in the rear face of each nipple-roll carrier, such racks being fitted for horizontal adjustment in their carriers; U, pinions upon the vertical screws pertaining to the rear housing, these pinions being secured to the screws at points in their length not needed for the purpose of the screws, the pinions engaging the racks T; V, screws serving to fix the racks to the nipple-roll carriers after adjustment; W, Figs. 8 and 9, flutes on the main rolls; a, the parallel portion of the tubular wagon-axle; b, the tapering portion thereof; c, the nipple thereof to receive the axle-nut; d, an elementary forming-roll, or, rather, a structure intended to illustrate a principle of construction which may be involved in the forming-rolls, such elementary roll being illustrated as consisting of two end portions or flanges only instead of having a continuous length, the two flanges being of course secured to the shaft, so as to revolve together; e, the flange of the elementary roll corresponding to the small end of the taper to be produced in the work in hand; f, the flange of the elementary roll corresponding to the large end of the taper to be produced, and g shallow notches in the periphery of the flange.

The driving-shaft G, revolving continuously, serves to transmit continuous rotary motion to the two main rolls in opposite direction, and at the same time serves in transmitting rotary motion to the top shaft, L, when the clutch Q is thrown, the direction of motion of the top shaft and the velocity of its rotation depending upon which way the clutch is thrown. The rotation of the top shaft serves in rotating the vertical screws M, and these screws serve in adjusting the distance between the main rolls. The gearing O and P is to be so arranged with reference to direction of motions that the opening of the rolls will take place much more quickly than the closing of the rolls. It follows that while the main rolls are revolving they may be quickly opened or slowly closed.

While the vertical screws are opening or closing the main rolls, the pinions U will serve in simultaneously opening or closing the nipping-rolls, the closing of all of the rolls taking place simultaneously; but it is obvious that as the opening and closing of the main rolls is effected by the screw-threads, while the opening and closing of the nipping-rolls is effected by the racks and pinions, the opening and closing of the nipping-rolls will take place much more rapidly than the corresponding opening and closing of the main rolls. The adjustment of the racks upon the nipping-roll carriers renders it possible to fix upon an adjustment for a predetermined distance between the nipping-rolls corresponding with a different predetermined distance between the main rolls.

Let all the rolls be opened. Heat the end of a metal tube for such length as requires condensation of diameter. Open the chuck F. Insert the metal tube through the chuck and endwise between the main rolls until the end of the tube lies between the nipping-rolls and about even with the rear ends of the main rolls. Then tighten the chuck. The driving-shaft being in continuous rotation, the main rolls will be continuously revolving. Throw the clutch so as to close the main rolls, and the main rolls will begin to approach each other slowly and powerfully, and their running peripheries will soon come in contact with the periphery of the stationary tube, the nipping-rolls meantime either standing at some distance from the tube, but moving toward it, or else, under certain circumstances of adjustment, making contact with the periphery of the tube at the instant the main rolls make such contact. When the revolving main rolls come in contact with the tube, rotary motion will be transmitted to the tube by the friction of the contact, and the chuck F, revolving in its bearing, will serve in supporting the outer portion of the tube and in furnishing the tube with its true bearing of rotation. While the main rolls and tube are thus revolving, the main rolls are gradually approaching each other, and the consequence is that the diameter of the tube, when in contact with the main rolls, will become reduced. Meanwhile the nipping-rolls are approaching each other, and the speed of their approach is greater than that of the main rolls. When they come in contact with the periphery of the metal tube, they will be revolved by the friction of contact, and by their inward movement will serve in reducing the diameter of the tube at the point where they engage the tube. By reason of their superior speed of approach they will, obviously, effect a greater reduction of the diameter of the tube than the main rolls will, and as a consequence the main rolls will reduce the diameter of the tube to a certain extent, and the nipping-rolls will reduce the diameter at the end of the tube to a greater extent, thus forming a nipple at the end of the tube. When the proper reduction of diameter has been effected, the clutch is to be thrown in the opposite direction, the rolls opened, the chuck is to be loosened, the tube withdrawn, a new tube inserted, and the operations are repeated as before.

Assume that it is desired to produce a tube having a diameter, near the nipple, of one and one-quarter inch, and having a diameter at the nipple of seven-eighths of an inch. The machine is to be adjusted for these sizes before beginning the operation upon the tubes. The main rolls are caused to approach each other until the distance between them at the proper point is an inch and a quarter, and they are caused to remain in this position for the time being. The screws V are loosened, thus freeing the nipple-roll carriers from the racks, and the carriers are pushed inward until the

distance between them is seven-eighths of an inch, after which the screws B are tightened. The machine is now adjusted for work. When the main rolls open, the nipple-rolls will also 5 open, but to a greater extent, and when the main rolls move inwardly to produce a tube of the diameter of an inch and a quarter the nipple-rolls will move inwardly to produce a tube of the diameter of seven-eighths of an 10 inch.

Either the main rolls or the nippling-rolls, or both, may have shapes or contours given to them to produce desired contours of the tube. For instance, in Fig. 5, it will be seen that 15 the outer end of the nippling-roll S has an ogee contour given to it. This will result in giving to the nipple-shoulder a shape substantially corresponding, and it is obvious that grooves in any of the rolls would serve in producing beads upon the tubes, and that beads upon the rolls would serve in producing 20 grooves in the tubes.

If it is desired to roll tapers upon the tubes—as, for instance, in the tapering spindles of 25 wagon-axles—the spaces between the main rolls will be formed tapering, either by tapering the rolls and placing their axes parallel or by using cylindrical rolls with their axes placed at angles with each other, the latter plan being 30 illustrated in Fig. 1.

I now come to the explanation of a peculiar principle of construction applicable to but not essential to main rolls for tapering work. Assume cylindrical main rolls running in contact with the tapering tube and driving the same by friction of contact. It is obvious that the rolls will tend to revolve the small end of the taper at a higher rate of speed than the large end, and that slipping and rubbing must 35 take place somewhere along the length of the taper between the rolls and the tube. For some kinds of tube material such action may result in the crimping of the tube and in rough surfacing and bad behavior generally.

45 It is obvious that main rolls having a properly-proportioned taper and running in contact with the tapering tube will produce equal travel of corresponding contact-surface at all points of the taper of the tube, and the slipping referred to will not take place; but it is 50 also obvious that such tapering main rolls, when running in contact with the parallel tube, would be open to the same objections as exist in connection with parallel rolls in contact with 55 a tapering tube. Therefore, as we begin operations with a parallel tube and finish the operations with a taper tube, the true remedy cannot be completely found in tapering rolls adapted for taper tubes, and when taper tubes 60 are produced with swelling contours the trouble increases.

I lessen the difficulty referred to by properly corrugating one or both of the main rolls, and the principle of the procedure will be explained 65 in connection with Fig. 7 of the drawings. In this drawing let *e* and *f* represent flanges of equal diameter, corresponding to the

two ends of the cylindrical roll shown as operating upon a tapering tube, *b*. *g* represents a series of notches or reliefs cut in the periphery of the flanges. When one of these notches comes opposite the tube, it is obvious that the flange will be free from contact with the tube.

It will be noticed in Fig. 7 that the right-hand flange is in contact with the tube. The left-hand flange is not in contact with the tube, the lack of contact being due to the fact that a relieved portion of the flange is opposite the tube.

Under such circumstances it will be obvious that at the instant of such condition the velocity of rotation of the tube will be controlled entirely by the right-hand flange. As the flanges continue to revolve together, the notch previously referred to in the left-hand flange

will have passed beyond the tube, and the periphery of that flange will engage the tube, and that flange will begin to affect the tube and its velocity of rotation; but at the instant the left-hand flange takes hold of the tube the right-hand flange lets go, by reason of the notch in

the right-hand flange coming opposite the tube. The velocity of the rotation of the tube will then be controlled entirely by the left-hand flange until the notch in the right-hand flange is passed and a new notch in the left-hand flange reached. Thus it will be seen that

neither of the flanges need slip upon or rub the tube, that the peripheral velocity of the tube will correspond precisely with the peripheral velocity of the flange which engages it,

that the tube will be driven first by one flange and then by the other, and that the speed of rotation of the tube will shift from fast to slow according to which of the flanges is driving it.

It will of course be understood that the flanges are to be provided with complete peripheral series of notches, and that as these notches

will seldom, if ever, make a second contact with the same point of the tube's periphery they

will not do harm by leaving marks upon the tube.

The arrangement of Fig. 7 may be defined, therefore, as a pair of flanges provided with notches so related to each other that when the notch of one flange is at the tube the unnotched portion of the other flange will be engaging the tube.

It should now be understood that we might secure a third notched flange midway between the two flanges shown and still carry out the same principle, the notches of the

three flanges respectively occupying a spiral relation to each other. It should now be apparent that we might add notched flanges between the two shown until we have formed a solid cylindrical roll, the notches of the flanges

forming spiral grooves in the roll. Having thus, by means of the elementary device illustrated in Fig. 7, illustrated the principle involved in the spiral fluted arrangement of the roll, it is sufficient to say that in practice the

principle may be carried out by simply providing the main rolls, one or both, with spiral flutes, the pitch of the spiral being such that a single portion only of the roll will make

frictional driving contact with the periphery of the tube at one time. Any form of flute thus spirally arranged will serve in realizing the principle; but the production of spiral flutes upon cylindrical or tapering roll-surfaces involves the use of more or less expensive machinery not found at hand in the machine-shop. I have therefore devised a system by means of which flutes having the spiral characteristics may be produced by a simple operation of straight planing or milling. This I will explain in connection with Figs. 8 and 9 of the drawings. Let it be assumed that the roll to be fluted has an uncut smooth surface. Mount the roll upon a planing or milling machine upon the usual character of centers, by means of which, as the work progresses, the circumferential division is effected. Put into the planing or milling machine a cutting-tool which under ordinary circumstances would cut a groove of the shape indicated at W in Fig. 9. If the roll should be fluted with such a tool, we would produce simply parallel flutes of the shape of the tool and of a depth corresponding to the depth to which the tool was fed inward during the cutting. Under such circumstances the desired flute having spiral characteristics would not be at all produced. Now lower one end of the roll as it is supported in the planer or milling-machine sufficiently to permit the cutting-tool to produce the full desired depth of the cut at one end of the roll without producing any depth of cut at the other end of the roll. Now, cut a flute, and the flute will be found to be tapering, as seen in Fig. 8, the flute having a certain width at one end of the roll and running out to nothing at the other end of the roll. It will be seen that both shores of such a flute form substantially spiral lines and produce the characteristic of spiral flutes. The groove thus planed or milled may be defined as a groove wider at its top than at its bottom, and having its bottom line in a plane at a greater distance from the periphery of the roll at one end than from the periphery of the roll at the other end. After a roll has been thus provided with grooves having certain depth at one end of the roll and running out to nothing at the other end of the roll, the roll may, if desired, be reversed endwise, or the highest end of the roll set so as to be lowest, and a set of grooves may be planed or milled between those already produced, thus forming upon the rolls ribs having both sides possessing the spiral characteristic.

Attention should be called to the fact that the purpose of the chuck F is simply to grasp and furnish a true bearing of rotation for varying sizes of tubes. Where the machine is intended for but one size of tube, it is obvious that they may be run directly in a properly-fitting bearing corresponding with the bearing E, and the chuck may be omitted.

I claim as my invention—

1. In a forming-machine, the combination, substantially as set forth, of a pair of rolls disposed alongside each other and leaving a

space between their peripheries, mechanism for imparting rotation to said rolls, housings for the support of the rolls, a roll-box for each journal of each roll fitted for movement in the housing so that both rolls may be uniformly moved and adjusted to and from each other, mechanism for adjusting the roll-boxes and thus effecting the opening and closing of the rolls, and a bearing for the tube disposed beyond one end of the rolls and having its axis disposed in a line passing lengthwise between the rolls. 70 75

2. In a forming-machine, the combination, substantially as set forth, of roll-housings, roll-boxes all fitted to slide therein, mechanism for adjusting the boxes uniformly in pairs in the housings, rolls fitted to revolve in said boxes, mechanism for imparting rotary motion to the rolls, a bearing disposed beyond one end of the rolls with its axis in a line passing lengthwise between the rolls, and a chuck journaled in said bearing and adapted to receive a tube whose rear end projects 90 through the chuck between the rolls. 80 85

3. In a forming-machine, the combination, substantially as set forth, of roll-housings, roll-boxes fitted to slide in said housings, screws engaging said roll-boxes and serving by their rotation to adjust the boxes in the housings, rolls journaled in the roll-boxes, a driving-shaft substantially parallel with the rolls, a worm upon the driving-shaft, and a pair of shafts at right angles to said driving-shaft 100 and provided with worm-gears engaging said worm and with worms engaging worm-wheels on the shafts of the rolls. 95 100

4. In a forming-machine, the combination, substantially as set forth, of roll-housings, roll-boxes all adjustable therein, screws for simultaneously adjusting all the boxes, a driving-shaft, gearing arranged to transmit rotary motion from the driving-shaft to the rolls, a shaft geared to said screws, gearing fitted to transmit rotary motion from the driving-shaft to said last-mentioned shaft in a direction corresponding to and slower with reference to that of the driving-shaft, so as to cause the screws to revolve either one way or the other 110 while the driving-shaft revolves continuously, and a clutch adapted to throw such last-mentioned gearing into action and determine the direction of rotation of the screws. 115

5. In a forming-machine, the combination, substantially as set forth, of rolls adapted to receive a tube lengthwise between them and to revolve the tube by frictional contact and to be themselves driven by power applied to them, means for adjusting the rolls simultaneously and uniformly to or from a plane disposed between the rolls during the rotation of the rolls, and a bearing beyond the ends of the rolls with its axis in said plane. 120 125

6. In a forming-machine, the combination, substantially as set forth, of rolls arranged to be driven by power and to receive a tube disposed lengthwise between them and to rotate the tube by frictional contact, and rolls

projecting from beyond one end of and along a portion only of said power-driven rolls, fitted to engage the periphery of such tube and be driven by frictional contact with the tube, and 5 means for adjusting said last-mentioned rolls to and from each other.

7. In a forming-machine, the combination, substantially as set forth, of roll-housings, roll-boxes adjustable therein, power-driven 10 rolls journaled in said boxes, means for adjusting the opening and closing of the rolls, roll-carriers, rolls carried by said roll-carriers and projecting along a portion only of said power-driven rolls and fitted to be revolved by frictional contact with the tube revolved by frictional contact with said first-mentioned rolls, 15 means for opening and closing said friction-driven rolls simultaneously with the opening

and closing of the first-mentioned rolls, and means for adjusting the relative distances of 20 approach of the two sets of rolls.

8. In a forming-machine, the combination of a pair of power-driven rolls disposed with their peripheries separated for the admission of a tube to be revolved by contact with said 25 rolls, one of said rolls having grooves, the margins of which grooves impress the tube spirally, substantially as and for the purpose set forth.

9. A roll provided with a flute wider and 30 deeper at one end of the roll than at the other, substantially as and for the purpose set forth.
